UNITED STATES PATENT OFFICE.

GREER M. SHEARER, OF CHICAGO, ILLINOIS, ASSIGNOR OF ONE-HALF TO FRANK H. TAYLOR, OF CHICAGO, ILLINOIS.

AUTOMATIC CONTROLLER CUT-OUT.

1,362,357.

Specification of Letters Patent. Patented Dec. 14, 1920.

Application filed February 17, 1917. Serial No. 149,320.

To all whom it may concern:

Be it known that I, GREER M. SHEARER, a citizen of the United States, and a resident of Chicago, in the county of Cook and State 5 of Illinois, have invented certain new and useful Improvements in Automatic Controller Cut-Outs; and I do hereby declare that the following is a full, clear, and exact description thereof, reference being had to the accompanying drawings, and to the characters of reference marked thereon, which form a part of this specification.

This invention relates to a novel controller cut-out adapted for any kind of a motor 15 control, either direct current or alternating current of any phase and is applicable for use in connection with cranes, hoists, elevators, electric vehicles and otherwise.

The purpose of the invention is to provide 20 means for making and breaking the circuit exterior to the controller fingers and contacts of the controller in such a way that the circuit is open both at the time when the fingers pass on to the first contacts and 25 at the time the fingers leave the contacts so as to thereby avoid arcing at the fingers, and which is particularly likely to occur as the fingers leave said contacts if the main supply circuit is closed, and 30 thereby avoid consequent destructive burning thereof without the necessity of using blow-out coils, insulating barriers and other safety devices within the controller.

A further object of the invention is to 35 provide a novel mechanism for mechanically controlling a cut-out switch for opening the circuit exterior to the controller, which mechanism is mechanically operated from the controller actuating device, as the usual 40 hand lever.

Another object of the invention is to provide a novel switch controlling mechanism of this character which is so arranged with respect to the operative position of the controller fingers that at any instant or at any 45 point in the operation of the controller when the hand lever is moved to shut off power, either forward or reverse, the cut-out switch is actuated to open the circuit and the controller can not again be advanced to pick up the load without return to the off point of the controller. This prevents picking up a heavy load at advanced points and over-loading the motor.

55 Other objects of the invention are to im-

prove and simplify controllers of this character, and the invention consists in the combination and arrangement of the parts shown in the drawings and described in the specification, and is pointed out in the appended claims.

In the drawings:—

Figure 1 is a diagrammatic view of one type of controller, developed in a flat plane, showing my invention applied thereto. 65

Fig. 2 is a top plan view of the cut-out switch controlling unit.

Fig. 3 is a side or edge elevation thereof.

Figs. 4, 5 and 6 are fragmentary plan views, separately shown, of the elements of 70 the controlling unit.

Fig. 7 is a fragmentary perspective view of the switch controlling unit.

The controller diagrammatically shown in Fig. 1 is adapted to a three phase motor circuit, but it is to be understood that my improvements may be adapted to any other practical form of controller, whether for alternating or direct current. It is also shown as adapted to a forward and reverse 75 type of controller wherein the operating lever is adapted to be moved from the central or off point of the controller in one direction for forward control and in the other direction for reverse control. The invention, however, is not limited to this particular type of controller.

The controller shown in Fig. 1 is developed for an eight point forward and an eight point reverse control and the contact 90 rings 10 are so arranged with respect to controller fingers (not shown) as to be electrically connected to the points 11 in a familiar manner. From the points 11 the various circuit wires 12 and 13 lead to the resistance elements and to the motor. 95

14, 15 and 16 designate the line wires of a three phase feed circuit. The wires 14 and 15 are connected in the controller and the wire 16 leads to the motor. Connected in 100 said lines 14, 15 and 16 are contactors or magnetic switches 17, 18 and 19 and blow-out coils 17', 18' and 19', the function of which latter is to blow out the arc between the contacts of said contactors. Said contactors include closing coils 20, 21 and 22, the functions of which latter are to close and open the main line circuit at said contactors. To said contactors is connected by suitable wiring a switch, designated as a whole by 110

23, and hereinafter to be described, and which operates the closing coils 20, 21 and 22 to open and close the circuit. Corresponding ends of said closing coils are connected in parallel by a wire 24 to the line wire 15, outside of the blowout coils and the other corresponding ends of said closing coils are connected in parallel by a wire 25 with one terminal of the switch 23. The 10 other terminal of the switch is connected by a wire 26 to the other wire 14 of the operating circuit which leads to the controller, the connection being outside of the associated blow out coil. The contactors or magnetic 15 switches may be of any preferred type, and inasmuch as their function is well understood by those skilled in the art, they need not be further described. The operating current of the switch 23 is sufficiently low 20 to prevent arcing at said switch 23, by reason of the resistance of the closing coils inserted therein.

The switch 23 may be of any suitable or preferred type. As herein shown it comprises a fixed block 28 of insulating material, one end of which carries one terminal plate 29 of the switch, to which the wire 25 is connected, and the other end of which carries a terminal plate 30 of the switch to 30 which the wire 26 is connected. 31 designates a switch blade which is pivoted at 32 to the terminal plate 29 and is in contact therewith. The other end of the switch blade is swingable toward and from the terminal 35 plate 30 and when in the position indicated by dotted lines in Fig. 1 is in electrical contact therewith to close the switch. The said switch 23 is a single step switch, in that it acts in one operation or step to cut in or 40 cut out the circuit exterior to the controller.

The said switch blade is provided with a tail piece 33 which is adapted to be connected with any suitable means that is mechanically operated by the controller lever, 45 or by other means by which the controller is actuated, so as to swing the switch blade into its open and closed positions. As herein shown the tail piece of the switch blade is loosely connected to the lower end of a link 50 35, the upper end of which link is loosely connected to one end of a lever 36. The link may be adjusted as to length by means of the right and left hand thread nut shown, or otherwise; and said link or its connections with the switch blade or lever 36 may be provided with an insulating barrier to prevent short circuiting of current from the switch to metallic parts associated with the lever 36. The lever 36 is pivoted between 55 its ends at 37 to a fixed bracket 38. The other end of said lever 36 is associated with mechanically controlled means, that are set in operation by the actuation of the controller drum, so constructed and arranged 60 that when the controller is adjusted with

its handle at the off point, the operating circuit is open by reason of the opening of the switch 23. When the controller operating handle or lever is operated to turn the controller, either in the forward or reverse 70 direction, the controller drum is first rotated to bring the first controller fingers of the series into contact with their respective controller rings at a time when said rings are dead, and thereafter the mechanical controlling means for the cut-out switch is operated to close the switch 23 and thereby close the main supply circuit exterior to the controller. The controller may now be advanced either in its forward or reverse throw 75 to bring the successive fingers into contact with their respective contact rings. Said mechanical controlling means for the cut-out switch is such, however, that at the instant the controller is adjusted to reduce or 80 shut off the current, the mechanical controlling means operates first to open the motor circuit before any of the fingers of the controller have broken connection with their respective controller rings, so that said rings 90 are dead when the contact between them and the fingers are broken. The switch controlling means is also so arranged that the controller can not be again advanced to pick up load without returning the controller to 95 its mid or off position and starting all over again from the first point, thereby preventing the motor picking up a heavy load at an advanced point.

The mechanically actuated cut-out switch 100 control mechanism for effecting these results, in connection with the lever 36, is herein shown as made as follows:—

Suitably connected to the shaft 40 of the controller drum are a series of upper, lower 105 and intermediate disks 41, 42 and 43. The upper and lower disks are of considerable thickness, with respect to the intermediate disk. As herein shown the said disks are mounted concentrically with respect to the 110 shaft 40 of the drum and are non-rotatively fixed to said shaft, they being provided with registering polygonal openings 44, 45 and 46, which fit the correspondingly shaped portion of the shaft 40. In some types of 115 controllers the said disks 41, 42 and 43 may be thus mounted on the shaft just beneath the top plate 48 of the controller casing and between the same and the drum. In other types of controller they may be mounted exterior to the controller casing and suitably connected to the drum operating shaft. In either event the said disks move in synchronism with the drum or at like angular distances with the drum in each adjustment of 120 the latter.

The upper disk of the cut-out controlling device is provided in its periphery, at both sides of a centrally disposed raised portion 50 with a series of ratchet shaped cam pro- 130

jections 51, the wider faces 52 of which are directed away from the central or mid portion 50 of the disk 41. The said wider faces 52 of the cam projections 51 are beveled downwardly and rearwardly as indicated in Figs. 1, 3, 4, and 7. The intermediate disk 42 is provided opposite to the oblique wider faces 52 of the cam projections 51 with notches 54, and the edges 5 of said notches are obliquely inclined to correspond to the inclination of the faces 52 of the cam projections of the upper disk 41. The periphery of the lower disk 43 is plain and concentric to the axis of the disk 10 throughout the principal portion thereof and is formed with a raised portion 56 which lies below the raised portion 50 of the upper disk 41. The intermediate disk 42 in its parts between the notches 54 extends radially beyond the periphery of the lower disk 43 and beyond the cam projections 51 of the upper disk. The said upper disk is provided, above the cam projections 51 with a solid flange 57 which extends 15 radially beyond said cam projections, and the lower disk is likewise provided at its lower side with a similar flange 58, so that there is formed between the upper flange 57 and the intermediate disk 42 an annular 20 groove or track, and between said intermediate disk and the lower flange 58 a like annular groove or track. Said flanges 57, 58 may form integral parts of the upper and lower disks respectively or may be 25 formed on plates which are attached in any suitable manner to said disks.

The lever 36 of the controlling mechanism is provided at its end adjacent to the group of disks with a pin 60 which is 30 adapted to extend unto the tracks of the controlling unit thus formed, said pin as herein shown extending loosely through an opening in the lever 36 and is backed by a spring 61 which urges the pin toward the 35 peripheries of the disks.

The lower disk 43 is provided in the lower track at the sides of its central raised portion 56 with ratchet-like cam projections 59, the wider faces 63 of which are directed 40 toward the central raised portion 56 and are beveled or oblique at angles corresponding to the inclination of the cam faces 52 of the upper disk. The said projections 59 are located just below the lower portions of 45 the cam projections 51 of the disk 41 next adjacent to the central or raised portion 50 of said disk and below the corresponding notches 54 of the intermediate disk 42; and the cam faces 63 of said projections 59 bear 50 such relation to said notches and to the oblique faces 52 of the cam projections 51 that when the disks are rotated in either direction from the central or off position 55 the engagement of the cam faces 63 of said 60 projections guides the pin 60 from the

lower track of the controlling unit formed by said disks to the upper track thereof. This has the effect to swing the forward end of the lever 36 upwardly and the rear end thereof downwardly, and said lever 70 acts, through the link 35, on the switch blade 31 to close the blade against the terminal 30 and to thereby, through the switch 23, close the circuit through the coils 20, 21 and 22 of the contactors and close the supply circuit. This action of the switch occurs after the first pair of contact fingers of the controller are brought into engagement with their respective contact rings; the respective contact fingers being brought 75 into contact with said rings as the pin 60 passes by the wider oblique faces of the respective cam projections 51 when moving away from the central raised portion 50 of the disk 41. The controlling unit may be 80 advanced to bring the successive fingers into contact with their respective rings until the highest speed is attained in the usual manner of such controllers.

By reason of the oblique faces 52 of the cam projections 51 in the upper track of said unit, the instant the controller drum is reversed to lower the speed of the motor 90 said oblique cam faces serve to force the pin 60 from the upper track to the lower track 95 of the controlling unit, and said pin acts, through the lever 36 and link 35 to open the switch 23, and thereby to open the main supply circuit. After the pin has been shifted from said upper track to the lower 100 track, which thus causes the operation of the controlling lever and the cut-out switch, the fingers corresponding to the cam projection which have been operative to open the cut-out switch move off their respective contact rings, so that arcing at the fingers and 105 rings is avoided. When the switch 23 has thus been operated to open the control circuit the pin 60 of the switch controlling device can not be again shifted upwardly into 110 the upper track of the controlling unit until the controller drum actuating handle is again swung to its central or off position and the controller is operated again from its lowest speed, so that it thereby becomes 115 impossible for the controller to be operated to pick up a load at an advanced point in the controller.

While the controlling unit described is herein shown as made of a plurality of 120 disks, it will be understood that the same may, within the purview of the invention, be made an integral part with the portions in the upper and lower tracks suitably shaped to constitute the central raised portions and the oblique cam portions described, and with the intermediate flange 43 provided with the notches 54 described.

It will be furthermore understood that the mechanical control mechanism described 130

may be employed with other types of controllers and may have other movement of translation than a rotary movement. Furthermore, where it is not convenient to mount 5 the cut-out switch controlling unit directly on the drum shaft, it may be connected to said drum shaft by any suitable mechanical means adapted to transmit the proper direction of movement to the controller unit 10 to actuate the cut-out switch controlling lever 36 or other equivalent member.

While reference has been made in the specification and in certain of the claims with respect to controlling the cut out switch, 15 so that said switch 23 is open both when the first fingers pass into their contact rings and when the fingers break contact with their rings in the reversal of the controller, it will be understood that the latter condition 20 is the one which is of real importance when operating with currents of normal or the most usable values, inasmuch as the arcing takes place when the fingers leave their contact rings when operating with current 25 of varying strength, while such arcing does not occur when the fingers move to the contact rings with the supply circuit closed unless the current is very heavy.

It is also to be understood that the various 30 details of construction shown may be otherwise varied within the spirit and scope of my invention and that the invention is not limited to such details, except as to the claims wherein the claims are specifically 35 set forth, and as imposed by the prior art.

The subject matter disclosed relating to the circuit connections between the feed and controller circuits and the controlling switch are not herein claimed but are made the 40 subject of a divisional application filed on the fifth day of April, 1919, Serial Number 287,860.

I claim as my invention:

1. The combination with a motor controller 45 embracing a movable controller member, its contact points and its manual operating device, of a low amperage switch adapted to control a feed circuit through said points, and a controller element in fixed 50 relation to said points and operable through said manual operating device for said controller member and having a positive mechanical connection to said switch and operating to close and to maintain the switch 55 closed between speed changes of the controller.

2. The combination with a motor controller 60 embracing a movable controller member, its contact points and its manual operating device, of a low amperage switch adapted to control a feed circuit through said points, and a controller element operable through said manual operating device for said controller member and having a positive 65 mechanical connection to said switch and op-

erating to close and to maintain the same closed between speed changes of the controller, and constructed with means to maintain the feed circuit closed throughout a continuous sweep of the controller element 70 from low to high speed and to open the feed circuit upon return of the controller member from any point of its sweep before a contact point has been separated from its coöperating contact point. 75

3. The combination with a motor controller embracing a movable controller member, its contact points and its manual operating device, of a low amperage switch adapted to control a feed circuit through 80 said points, and a controller element operable through said manual operating device for said controller member and having a positive mechanical connection to said switch and operating to close the same and maintain it closed between speed changes of the controller, and constructed with means to open said switch only when said controller member is reversed prior to separation of a contact point with its coöperating contact 85 point, and to permit said switch to be again closed only when the controller member is returned to off position and again advanced toward high speed. 90

4. The combination with a motor controller embracing a movable controller member and its contact points, of a low amperage switch adapted to control a feed circuit through said points, a controlling element movable in synchronism with said member, and means providing a positive mechanical connection between said element and said switch, said controlling element and connecting means being constructed to control said switch to maintain it closed between speed changes of the controller to thereby maintain the feed circuit closed through 100 said contact points throughout a continuous sweep of the controller member from low to high speed and to open the feed circuit 105 upon return of the controller member from any point of its sweep only before a contact point has been separated from its coöperating contact point.

5. The combination with a motor controller embracing a movable controller member and its contact points, of a low amperage switch adapted to control a feed circuit through said points, a controlling element movable in synchronism with said member, means providing a positive mechanical connection between said element and said switch, said controlling element and connecting means being constructed to control said switch to maintain it closed between speed changes of 115 the controller to thereby maintain the feed circuit closed through said contact points throughout a continuous sweep of the controller member from low to high speed and to open the feed circuit upon return of the 120 125 130

controller member from any point of its sweep only before a contact point has been separated from its co-operating contact point, and means permitting said switch to be 5 again closed only when the controller member and said switch controller element are returned to off position and again advanced toward high speed.

6. The combination with a motor controller embracing a movable controller member and its contact points, of a low amperage switch adapted to control a feed circuit through said points, a controlling element movable in synchronism with said member, 10 and means providing a positive mechanical connection between said element and said switch, said controlling element and connecting means being constructed to control said switch to maintain the feed circuit closed 15 through said contact points throughout a continuous sweep of the controller member from low to high speed and to open the feed circuit upon return of the controller member from any point of its sweep before a contact point has been separated from its co-operating contact point, and constructed to close said switch after the low speed contacts are brought into engagement in the advance movement of the controller member.

30 7. The combination with a motor controller embracing a rotating controller member and its contact points, of a low amperage switch adapted to control a feed circuit through said points, a controller element fixed to rotate with said member and having controlling cams appropriated one to each of said contact points, and means providing a positive mechanical connection between said element and said switch and operated by 35 said cams, said cams operating on said connecting means to open said switch upon return movement of the controller member from any point of its sweep, and to again close said switch only after the controller 40 member has been returned to off position and again advanced toward high speed and to maintain the switch closed between speed changes of the controller.

8. Controlling mechanism for the controlling switch of an electrical controller comprising a controlling unit, having spaced tracks, a member having means to connect it to said switch and provided with a projection adapted to separately enter said 50 tracks and cams in said tracks to shift said projection from one track to the other.

9. Controlling mechanism for the controlling switch of an electrical controller comprising a controlling unit, having spaced 55 tracks, a member having means to connect it to said switch and provided with a projection adapted to enter said tracks and cams in said tracks to shift said projections from one track to the other, said tracks and 60 cams being so arranged that when said pro-

jection is shifted from one track to the other it can re-enter the first track only after the said unit has been returned to off position.

10. Controlling mechanism for the controlling switch of an electrical controller 70 comprising a rotative member provided with spaced tracks and with cam projections in said tracks, an oscillating member having means to connect it to said switch, and a projection in said oscillating member adapted to enter said tracks and to be shifted by said cam projections from one track to the other.

11. Controlling mechanism for the controlling switch of an electrical controller 80 comprising a controlling unit, having spaced tracks, a member having means to connect it to said switch and provided with a projection adapted to engage said tracks, one of said tracks being provided with a series 85 of cams for contact with said projection and appropriated to the respective points of the controller and over which said projection rides in the advance of the controller from low to high speed, said cams being shaped to 90 shift said projection from one track to the other when said controlling unit is reversed and to permit said projection to enter the first mentioned track only when the controlling unit has been adjusted to off position. 95

12. Controlling mechanism for the controlling switch of an electrical controller comprising a controlling unit, having spaced tracks, a member having means to connect it to said switch and provided with a projection adapted to engage said tracks, one of said tracks being provided with a series 100 of cams for contact with said projection and appropriated to the respective points of the controller and over which said projection rides in the advance of the controller from low to high speed, the cams of the latter track being shaped to shift said projection to the other track upon reverse movement of said unit, and the latter track being provided 105 with a cam to shift said projection therefrom to the other track in the initial movement of said unit.

13. In a controller, a movable controlling unit provided with spaced tracks, and a 115 member adapted to enter said tracks for operating a cut-out switch, one of said tracks being provided with an off-point face and with cams to correspond with the respective points of the controller, and the other of 120 said tracks being provided with an off-point face and with a cam to shift said projection from the latter track to the other track, and the cams of the latter track being so shaped that reverse movement of said unit serves 125 to shift said projection from the last named track to the other track.

14. In a motor control, a rotative drum type controller member having contact points adapted by rotative movement there- 130

of to be progressively shifted into contact with fixed contact points from low to high speed, a low amperage controlling switch for a feed circuit, a cammed unit operatively connected to and actuated in synchronism with said controller member, and a swinging member coacting with and actuated by said cammed unit and providing a positive mechanical connection for controlling said switch to maintain it closed between speed changes of the controller.

15. Controlling mechanism for a low amperage controlling switch of an electrical controller, comprising, in combination, a rotative controller member having contact points adapted by rotation of the member to be progressively shifted in contact with fixed points from high to low speed, a controller unit fixed to and rotating with said member, and means providing a positive mechanical connection between said unit and said switch constructed to maintain said switch closed through the range of said controller member from low to high speed.

20 16. Controller mechanism for the controlling switch of an electrical controller comprising a rotative unit having peripheral, spaced tracks, cam elements in said tracks,

and a connection between said switch and unit having a projection adapted to enter 30 said tracks and to be deflected by said cams from one track to the other.

17. Controller mechanism for the controlling switch of an electrical controller comprising a rotative unit having peripheral, 35 spaced tracks, cam elements in said tracks, one corresponding to the off-position of the controller and the other as a series angularly spaced to correspond to the points of the controller, and a member connected to 40 said switch and having a projection adapted to enter said tracks and to be shifted from one track to the other by the off-position cam element, and to be shifted from the latter track to the first track by the other 45 cam elements of the series.

In witness whereof I claim the foregoing as my invention, I hereunto append my signature in the presence of two witnesses at Chicago, Illinois, this 5th day of February, 50 1917.

GREER M. SHEARER.
